UNITED STATES PATENT OFFICE.

JOHN BRACHE LE MAITRE, OF NEAR BIRMINGHAM, ENGLAND.

DOOR AND WINDOW FOR CARRIAGES.

SPECIFICATION forming part of Letters Patent No. 727,978, dated May 12, 1903.

Application filed December 5, 1902. Serial No. 134,013. (No model.)

To all whom it may concern:

Be it known that I, JOHN BRACHE LE MAITRE, a subject of the King of Great Britain, residing at 45 Grantham road, Sparkbrook, near Birmingham, in the county of Warwick, England, have invented certain new and useful Improvements in Doors and Windows for Carriages and to the Mode and Means for Operating the Same, of which the following is a specification.

My invention has for its object improvements in and relating to railway-carriage and other windows and to the mode and means for operating the same, by which such windows and sashes can be raised and lowered or fixed in any intermediate position with greater facility.

In order that my invention may be clearly understood and more easily carried into practical effect, I have appended hereunto two sheets of drawings, upon which I have illustrated an example of the construction and operation as applied to a railway-carriage window.

Figure 1 is a front elevation of the inside of a railway-carriage door and window, the window being in its lowered position. Fig. 2 is an enlarged broken-off elevation of the same door with part of the woodwork removed, so as to show the mechanism more clearly. Fig. 3 is a plan of the operating mechanism, which is fixed to the upper part of the door. Fig. 4 is a cross-section of the mechanism on the line A B.

The door-frame *a* with its window *b* illustrates such a door and window as are at present used in railway-carriages, and my invention is to dispense with the old leather strap for raising and lowering the window, which according to my invention is accomplished by a sliding motion. In Figs. 1, 2 the window *b* is raised and lowered by sliding the handle *c* laterally along the slide-bar *d* of the plate *e*, which may be curved, as shown by dotted lines, Fig. 1. At the back of the plate *e* is mounted a pulley-wheel *f*, over which an endless chain *g* or its equivalent passes. At the other end of the bar *e* is mounted a sprocket-wheel *h*, also over which the endless chain *g* passes. Fast with *h* on the same spindle are the sprocket-wheel *i* and the ratchet-wheel *j*. Over the sprocket-wheel *i* the endless chain

or its equivalent *k* passes downward inside the framework of the door and is secured to the lower end of a spur or bracket *l*, which is fastened to the window-frame *b* by a pin *m*. The lower portion of the endless chain *k* passes around a small pulley *n*, hung against the inside of the door. The action of raising and lowering the window *b* is now very simple, for as the handle *c*, attached by the screw *o* to the endless chain *g*, as seen at Fig. 1, is moved along the bar *d* of the plate *e* to the position it occupies in Fig. 2 the window is raised, as seen in the latter figure, and it is lowered by the reverse motion of the handle *c*. In order to secure the window in its closed or top position or in any intermediate position, I attach a pawl-lever *p*, which is pivoted at *q*, the point of the pawl taking into the ratchet-wheel *j*. The tail of the pawl is kept in its normal position, as shown at Fig. 2, by the spring, so that the window is automatically locked by the pawl in any position it may happen to be. The window may of course be raised while the pawl is in the ratchet. If, however, it is required to lower the window, the knob or push *r* is pressed inward, and the nose *s* is so formed, as shown at Fig. 4, that the tail of the pawl is depressed and the point lifted free of the ratchet-wheel *j*, thus allowing the window to be lowered; but immediately the pressure is removed from the knob *r* the pawl falls into the ratchet and locks the window in any desired position. The slide-bar and pulleys may, if desired, be mounted on wood or other material instead of the metal frame.

I have shown my invention applied only to a railway-carriage door and window; but it is also applicable to hansom-cabs and other vehicles with such doors and windows.

What I claim, then, is—

1. The combination with a window, of a suitable frame having a transverse slot, a handle movable in said slot, pulleys adjacent to each end of said slot, an endless chain attached to said handle and running over said pulleys, and another endless chain driven by one of said pulleys and attached to the window.

2. The combination with a window, of a suitable frame having a transverse slot, a handle movable in said slot, pulleys adjacent

to the ends of said slot, an endless chain attached to said handle and running over said pulleys, another endless chain driven by one of said pulleys and attached to the window, 5 a ratchet-wheel on the shaft of one of said pulleys, and a detent-pawl engaging with said wheel.

3. The combination with a window, of a suitable frame having a transverse slot, a 10 handle movable in said slot, pulleys adjacent to the ends of said slot, an endless chain attached to said handle and running over said

pulleys, another endless chain driven by one of said pulleys and attached to the window, a detent-lever for locking said pulleys and 15 chain, and a push-button having a cam-surface for releasing said lever.

In witness whereof I have hereunto set my hand in presence of two witnesses.

JOHN BRACHE LE MAITRE.
